UNITED STATES PATENT OFFICE.

WAYNE SONDLEY RAY, OF ASHEVILLE, NORTH CAROLINA.

DESIGN FOR A HORSE-BOOT.

SPECIFICATION forming part of Design No. 22,955, dated December 5, 1893.

Application filed October 4, 1893. Serial No. 487,183. Term of patent 3½ years.

To all whom it may concern:

Be it known that I, WAYNE SONDLEY RAY, a citizen of the United States, residing at Asheville, in the county of Buncombe and State of North Carolina, have invented and produced a Design for a Horse-Boot; and I do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to a design for horse boots, the said boot having a base portion, and an ornamental band surrounding the said boot between the base and upper portions, and the said base portion conforms in shape to that of a horse's hoof, and on the base of the said rigid portion is a horse-shoe shaped elevation, running parallel with the outline of the base portion.

To this end the invention consists in the design which is illustrated in the accompanying drawings, which form a part of this specification, and in which—

In Figure 1 I have shown a perspective view, and Fig. 2 shows a bottom plan view of the boot.

Reference being had to the drawings, A

represents a base portion conforming in shape to that of a horse's hoof, and E designates an upper portion with low cut scallops extending nearly to the base portion of the boot, and entirely around the circumference of the said boot.

C is an ornamental band about the boot between the base and upper portions of the same, and in the scallops near the tips are slits, and a is a horse shoe shaped elevation running parallel with the outline of the base portion.

The leading features of the design are a horse boot, having a base portion conforming in shape to a horse's hoof, a horse-shoe-shaped elevation on the base conforming to and parallel with the outline of the base portion, and an upper portion having a series of scallops extending around the said boot, and between the said base and upper portions is provided an ornamental band.

What I claim to be new, and desire to secure by Letters Patent, is—

The design for a horse boot substantially as shown and described.

In testimony whereof I affix my signature in presence of two witnesses.

WAYNE SONDLEY RAY.
